INVENTOR:

Frank B. Cook.

UNITED STATES PATENT OFFICE.

FRANK B. COOK, OF CHICAGO, ILLINOIS.

CABLE-TERMINAL.

No. 861,812.

Specification of Letters Patent.

Patented July 30, 1907.

Application filed February 23, 1907. Serial No. 353,944.

To all whom it may concern:

Be it known that I, FRANK B. COOK, a citizen of the United States of America, residing at Chicago, in the county of Cook and State of Illinois, have invented a new and useful Cable-Terminal, of which the following is a specification, reference being had to the accompanying drawings, illustrating same.

My invention relates to cable terminals employed in connections with cables of various kinds for distributing the cable conductors and connecting same with the line conductors.

The principal objects of my invention are to provide a cable terminal constructed of two similar halves adapted to be secured together to form an inclosed terminal; to provide improved means in a cable terminal for distributing the conductors of the cable leading to the terminal; to provide an improved cable terminal of the inclosed-head type constructed of porcelain; to provide improved means for accommodating and insulating the cable and the aerial conductors leading to the cable terminal; and to provide compactness, simplicity of construction, and durability in such a cable terminal. Other objects will be apparent from the following specification.

25 In the accompanying drawings illustrating the preferred form of my invention, Figure 1 is a side elevation of the cable terminal of the invention; and Fig. 2 is a cross-sectional view of the terminal, taken on line x-x of Fig. 1, with portions shown in elevation.

30 Like characters refer to like parts in the several figures.

The terminal head is constructed of two similar halves 1 1 bolted together by bolts 2 2 preferably as shown in Fig. 2, with suitable gaskets 3 3 placed between the halves 1 1 to make an air-tight and moisture-tight joint. Each half 1 is provided with half holes 4 5 and 6 at the bottom end, and 7 at the top end, adapted to form holes 4 4 and 5 5 to accommodate the aerial conductors leading to the terminal, hole 6 6 to accommodate the cable leading to the terminal, and hole 7 7 through which the cable head may be filled with an insulating compound, when the two halves 1 1 are placed together. The gaskets 3 3 are preferably made in two straight strips, which extend along the side of the terminal from the outer end of hole 6 6 to the outer end of hole 7 7, holes 6 6 and 7 7 being preferably the same size.

8 8 indicates the inclosure of the terminal head adapted to accommodate the cable conductors and which is preferably to be filled with the insulating compound. A cork 9 is provided for the hole 7 7, to close same after the terminal has been properly installed. Each half 1 is provided with recesses 10 10, preferably square or hexagonal, adapted to fit heads 11 11 of hollow bolts 12 12 to keep the bolts from turning. On the exterior surface of each portion 1 are provided

hubs 13 13 through which bolts 12 12 extend. The bolts 12 12 are secured in place by nuts 14 14, 15 15 being binding nuts to clamp the aerial conductors 16 16 to the bolts 12 12. Each half 1 is provided with two projecting edge portions 17 17 over which the sheet-metal cover 18 is placed to inclose the terminal as a whole. Each projecting edge portion 17 is provided with a series of holes 19 19 therethrough adapted to accommodate the aerial conductors 16 16 which lead from the 60 holes 4 4 and 5 5 in the base of the terminal, through holes 19 19 in the portions 17 17 to bolts 12 12. The cable is inserted into the hole 6 6 in the base of the terminal, the wires 22 22 of the cable being distributed to and through the hollow bolts 12 12 and soldered at the 65 outer ends of bolts 12 12 by solder 20 which completely seals the openings 21 21 of the hollow bolts 12 12 and thereby seals the inclosure 8 8 of the terminal air and moisture tight.

It will readily be seen that each circuit through the 75 cable terminal is from a cable conductor 22 through a hollow bolt 12 and an aerial conductor or bridle wire 16 which extends through a hole 19 in a portion 17 and through one of the holes 4 4 or 5 5 in the base of the terminal. The hubs 13 13 are for the purpose of 80 increasing the insulation between the terminal, bolts 12 12. Each half 1 of the terminal is provided with a half circular base portion 23 which is suitably bolted to a mounting bracket 24 by bolt 25, the bracket 24 being cut away as at 26 26 to accommodate the flat 85 projecting portions 27 27 of the two halves 1 1 of the terminal, which project below the mounting bracket 24 as shown in Fig. 1. The sheet metal cover 18 preferably rests on the back portion 28 and the front corner portions 29 29 of the bracket 24 which support 90 the cover in proper position. The portions 27 27 projecting below the mounting bracket 24 thoroughly insulate the conductors extending through holes 4 4, 5 5 and 6 6 from the metal mounting bracket 24. The hole 6 6 being preferably long, forms a guide for the 95 cable to hold same in proper vertical position. The cable leading to the terminal is preferably somewhat smaller than the hole 6 6, the insulating compound used in the terminal filling the space between the cable and the hole 6 6 so as to make a tight joint and 100 hold the cable rigidly in place.

In installing the terminal, one of the halves 1 1 is unbolted from the mounting bracket 24 and moved away from the other half 1 sufficiently to allow the cable to be placed between the halves 1 1 and the 105 conductors 22 22 thereof distributed through the hollow bolts 12 12. After the conductors 22 22 are thus distributed, the two halves are bolted together as shown in Fig. 2, by bolts 2 2. The conductors 22 22 are then soldered to the bolts 12 12 at 20 20, the solder 110 sealing up all of the openings 21 21 in the bolts 12 12. The inclosure 8 8 may now be filled with an insulat-

2
ing compound, and then the cork 9 put into the hole 7 to close same.

It will readily be seen that the terminal may be used with only sufficient insulating compound to seal the cable in the hole 6 6, the inclosure 8 8 being sufficiently air and moisture tight to protect the paper-covered cable conductors from moisture. As the work of soldering the cable conductors 22 22 to the bolts 12 12 is done on the exterior of the terminal, the inclosure 8 8 may be very small, in fact just large enough to suitably carry the cable conductors, not providing any space within the terminal for making connections therein.

It will readily be seen that the terminal of my present invention is very simple to manufacture, it only being necessary to assemble the bolts 12 12 in two similar porcelain castings 1 1 and then bolt the castings 1 1 together.

It will also be seen that this cable terminal is absolutely fire-proof, there being no inflammable material used in its construction.

I do not wish to limit this invention to the particular details of construction as herein shown, as many modifications may be made therein without departing from the scope of the invention.

What I claim as my invention and desire to secure by Letters Patent is:

1. A cable terminal of the character described, comprising two porcelain halves secured together to form an inclosure for the cable conductors, terminal posts extending through the wall of each said half, and suitable fanning strips formed on the said halves, through which aerial conductors may be inserted and connected to the terminal posts.

2. A cable terminal of the character described comprising two similar porcelain halves secured together to form an inclosure for the cable, binding posts extending from the interior to the exterior of the inclosure in each of the

said halves, edge portions on the said porcelain halves to be used as fanning strips for aerial conductors, and holes 45 in the said edge portions for accommodating the aerial conductors leading through the said fanning strips to the said binding posts.

3. A cable terminal comprising two porcelain halves secured together to form an inclosure for the cable conductors, a circular base formed by the said halves being placed together, suitable holes through the said base formed by the said halves being placed together, for accommodating the cable and aerial conductors leading to the terminal, and means for suitably connecting the aerial conductors to the cable conductors through the walls of the said inclosure.

4. A cable terminal comprising two porcelain halves provided with series of terminal posts by means of which aerial conductors are connected to the cable conductors, 55 a circular base portion formed by the two halves, a mounting bracket to which the base portion is secured, a projection on the base portion extending through the mounting bracket, and holes through the said base portion and projection, formed by the two halves of the terminal, for accommodating the cable and aerial conductors leading to the terminal.

5. A cable terminal comprising two porcelain halves secured together with a gasket between to form an inclosure for cable conductors, each half being provided with series 65 of hubs thereon and fanning strips adapted to accommodate aerial conductors leading to the terminal, and series of binding posts extending through the said hubs whereby the cable conductors may be electrically connected with the aerial conductors.

6. An inclosure cable terminal comprising two similar porcelain halves mounted on a suitable base, fanning strips on the said halves formed as parts thereof, and suitable binding posts extending through the wall of each 75 half for connecting the aerial conductors to the cable conductors.

As inventor of the foregoing, I hereunto subscribe my name in the presence of two subscribing witnesses, this 20th day of February, 1907.

FRANK B. COOK.
